UNITED STATES PATENT OFFICE.

JOSEPH F. CULVERWELL, OF WASHINGTON, DISTRICT OF COLUMBIA, ASSIGNOR OF ONE-HALF TO LOUIS G. JULIHN, OF WASHINGTON, DISTRICT OF COLUMBIA.

STORAGE-CABINET FOR PHONOGRAPHIC DISK RECORDS.

1,311,322.

Specification of Letters Patent. Patented July 29, 1919.

Application filed December 18, 1915. Serial No. 67,559.

To all whom it may concern:

Be it known that I, JOSEPH F. CULVERWELL, a citizen of the United States, residing at Washington, in the District of Columbia, have invented certain new and useful Improvements in Storage-Cabinets for Phonographic Disk Records, of which the following is a specification.

This invention relates to a novel storage 10 cabinet for phonograph disk records.

The object of the invention is to construct a record cabinet in which storage space will be economized, the records properly protected and their individual selection 15 and removal facilitated.

It may be stated, by way of premise, that the proper protection, economical storage and convenient selection of disk records has presented problems, to which considerable 20 thought has been directed. The well known method of storing these records in books, requires the individual selection of the book, the handling thereof and subsequently the removal of the record and the reversal of 25 this inconvenient operation to restore the record after its use. A simple mode is the storage of the records in individual vertical compartments with their peripheries projecting sufficiently to enable them to be 30 grasped by the operator and withdrawn. This, while a distinct improvement, is not economical in the matter of storage space, because the records must be spaced sufficiently to enable each record to be readily 35 grasped. An attempt to avoid this wide spacing of the records has been made by providing various forms of ejecting devices by means of which any one of a series of closely spaced coaxial records may be projected sufficiently to enable the operator to 40 grasp its edge and complete its withdrawal.

My invention is directed to a novel storage cabinet allowing an arrangement of the records which, while permitting them to be 45 stored in comparatively close relation, will expose a portion of the edge of each record in comparatively widely spaced relation to the next adjacent coaxial record, so that any desired record may be readily selected, 50 grasped and withdrawn without sacrificing storage space, and without the necessity for employing ejecting mechanism.

In the accompanying drawings,

Figure 1 is a front elevation of the cabinet 55 herein described, parts being broken away.

Fig. 2 is a sectional view of the cabinet.

Fig. 3 is a perspective view of a portion of the cabinet.

Fig. 4 is a perspective view of a group of details of the cabinet, the parts being separated to more clearly show the construction. 60

In the accompanying drawings is shown a cabinet, 1, having an open front, 2, and having its top and bottom walls, 3 and 4, formed with grooves, or kerfs, 5, for the reception 65

of sheet metal or other partitions, 6. Each partition has cut and bent from its rear edge a buffer and spacer lug, 7, which forms a stop for a record, X, and contacts with an adjacent partition. These lugs are disposed 70

in three groups to accommodate the three groups of records located between the partitions. The records of the intermediate and upper groups are carried by longitudinally inclined supporting flanges, 8, cut and bent 75

from the partitions and serving also as spacers while the records of the lowest group are supported by the bottom, 4, of the cabinet, which is provided with spaced upstanding portions, 4^a, having their upper faces in- 80

clined downwardly to the rear to facilitate the complete return of the records to their proper positions. 85

Thus, when the records, X, are passed edgewise into the compartments, 6^a, they will 90 be arranged in close lateral relation but in groups located in different vertical planes with the records of each group alternating with those of the other group.

This arrangement will present the axes of 95 all records in the same vertical plane since they all rest against the spacer lugs, 7, and will cause a portion of each record to project beyond the peripheries of the two next adjacent records and thus enable it to be 100 grasped and easily removed from the cabinet.

As will be seen by reference to Figs. 2 and 105 3, the records, while arranged in a closely spaced series, economizing storage space, have each a well defined accessible grasping portion separated from the two next laterally adjacent grasping portions of other records by intervals equal to the distance between alternate records of the series. Stated 110 differently, the series of stored records is divided into three groups, the records of each group being twice as widely spaced for handling as the records of the series are spaced for storage. To facilitate the com-

plete return of the records to their proper positions, the supports, 8, are inclined downwardly toward the back of the cabinet.

The basic thought, underlying this invention, may be fully comprehended by reference to Figs. 2 and 3 and obviously is fundamental to a wide variety of modification of the instrumentalities whereby the records may be closely stored, yet widely spaced for handling.

It is only essential that the records be held separated completely and certainly and that their arrangement be such that each individual record may be made more accessible for handling than is purposed by the lateral spacing of adjacent records.

What I claim is:

1. A phonographic record cabinet having three series of individual disk record supports, each series of supports being arranged in a horizontal plane different from the horizontal planes in which the other two series of supports are arranged, and each pair of supports of a given series being located in vertical planes spaced apart to accommodate another pair of record supports belonging to two different series, whereby when three longitudinal series of vertically disposed disk records are mounted on the supports thus arranged, each record will have

an exposed grasping portion spaced from the next adjacent records by intervals or spaces, each of which is equal to the space required for the storage of two records.

2. A phonographic record cabinet having a rearwardly inclined bottom, and a series of parallel, vertical partitions spaced apart to accommodate individual records, certain of said partitions having rearwardly inclined record supports, the supports on adjacent partitions being located in different horizontal planes, and backstopping means for the records, whereby phonographic disk records accommodated between the partitions and supported by the bottom thereof, and by the supports will be arranged in three series, with each of the individual records of each series having a grasping portion non-coincident with the grasping portions of the records of any other series and spaced from the adjacent records of the same series by intervals, each of which is equal to the storage space required for two records.

In testimony whereof I affix my signature in the presence of a witness.

JOSEPH F. CULVERWELL.

Witness:

R. M. PARKER.
